ELEVATOR CONTROL DEVICE

Frederick A. Pavone, Brooklyn, N. Y.

Application December 19, 1931, Serial No. 582,035

11 Claims. (Cl. 187—29)

This invention relates to elevator control apparatus and particularly to an auxiliary control for use when testing the elevator cables or doing other maintenance or repair work in the elevator shaft.

One of the objects of the invention is to provide an auxiliary control for an elevator which may be operated from the roof of the elevator car.

10 Another object of the invention is to provide an auxiliary controlling device for an elevator which when in use automatically renders the regular elevator control inoperative.

A still further object of the invention is to provide 15 an auxiliary control for an elevator which limits the speed of the elevator to the slower speeds only both up and down.

Other objects of the invention and objects relating particularly to the construction and assembly of the various parts will be apparent as 20 the description thereof proceeds.

One embodiment of the invention has been illustrated in the accompanying drawings, in which:

25 Fig. 1 is a sectional side elevation of an elevator supported for vertical movement in its shaft and with the device of the invention incorporated;

Fig. 2 is a sectional front view of the auxiliary control box;

30 Fig. 3 is a sectional side view of the control box shown in Fig. 2;

Fig. 4 is an electrical wiring diagram showing the manner of connecting the auxiliary control 35 to the elevator control;

Fig. 5 is a perspective view of the receptacle used for making the connection;

Fig. 6 is a perspective view of the plug adapted to fit the receptacle of Fig. 5;

40 Fig. 7 is a sectional view showing the interior of the receptacle of Fig. 5; and

Fig. 8 is a sectional view taken on the line 8—8 of Fig. 5 and showing the plug in its connected position with the receptacle.

45 When testing or inspecting the cables of an elevator or oiling the shaft guides, or other equipment it is often necessary for the mechanic to stand on the roof of the elevator while an operator in the car runs the elevator up or down in accordance with the instructions of the mechanic on the roof. This process is dangerous inasmuch as it depends on the operator in the car correctly interpreting the instructions of the man on the roof to go in the proper direction and 50 at the proper speed. It is also possible for the

operator in the car to start the car at full speed either up or down when the mechanic on the roof is not expecting it with consequent danger to him. In addition to these disadvantages the process requires the employment of two men for 5 work which may be simply accomplished by one man providing he can control the movement of the car.

The invention, therefore, broadly consists of an auxiliary control device which may be removably mounted on the top of the car so that it can be easily reached from any position on the roof and including automatic means to disconnect the control apparatus inside of the car to prevent anyone from moving the car while the 15 man is working on the top.

Referring now more specifically to the drawings an elevator car 10 is shown mounted for vertical movement in a shaft 11, in the usual manner well known in the art, and supported by 20 cables 12. A control box 13 is shown mounted on two supports 14 extending to the floor 15 of the car and through one of these supports, which are preferably tubular, extends the cable 16 by means of which electrical connection is 25 made between the control box and the driving mechanism positioned at the top of the shaft. This driving mechanism has not been illustrated as it may be any of the well known types of driving apparatus used for the raising and lowering 30 of elevators.

A receptacle 17 is mounted adjacent the control box 13 in the wall of the elevator car and is connected to the control box by means of a cable 18. This receptacle contains the automatic 35 switch for disconnecting the main control box 13 and also the contacts for making the connection to the auxiliary control and will be described more in detail hereinafter.

The auxiliary control comprises a control box 40 19 attached to a cable 20 upon the other end of which is mounted the plug 21 for insertion in the receptacle 17 whereby the auxiliary control 19 becomes operative and the regular control 13 becomes inoperative.

45 The regular control box 13 is shown diagrammatically in Fig. 4 and comprises an arm 22 which is pivoted at 23 for limited rotary movement. A contactor brush 24 is mounted in the other end of the arm 22 beyond the pivot 23 and sweeps 50 in an arc over a plurality of contacts which operate relays in the driving mechanism in a manner well known in the art. Thus a central contact 25 is adapted to be connected to the power side of the circuit while a plurality of contacts 26, 27, 28, 55

29, and 30 are connected by means of wires 31, 32, 33, 34, and 35 to relays which when operated connect the power through successively diminishing resistances to the motor to operate it in the "up" direction. Similarly a plurality of contacts 36, 37, 38, 39, and 40 are connected by means of wires 41, 42, 43, 44, and 45 to relays which when operated connect the power through a series of diminishing resistances to the motor so as to drive it in a "down" direction. Thus when the arm 22 is moved toward the down position or in a clock-wise direction the main brush 24 bridges the power contact 25 and successively the contacts 26, 27, 28, 29, and 30, thus starting the car downwardly and increasing its speed up to the contact 30. In the same manner when the arm 22 is moved in a counter-clockwise direction toward the up position the contact 24 bridges the power contact 25 and successively the contacts 36, 37, 38, 39, and 40, thus starting the car upwardly and increasing its speed as the successive contacts are bridged. This construction is well known in the art and is no part of the present invention.

25 The receptacle 17 positioned adjacent the control box 13 may, if desired, have the same number of contacts as is provided in the main control box 13 but preferably I reduce the number of these contacts so as to eliminate the high speeds to 30 make it impossible to travel fast when the mechanic is on the top of the car. In the present instance I have shown three contacts on each side for the up and down movements of the car instead of the five on each side which have been 35 illustrated in the main control box 13. Thus contacts 46, 47, and 48 are connected respectively to the "up" contacts 36, 37, and 38 by means of the wires 49, 50, and 51, while the contacts 52, 53, and 54 are connected respectively to the down 40 contacts 26, 27, and 28 by means of the wires 55, 56, and 57. These contacts, shown diagrammatically in Fig. 4, are more accurately represented in Figs. 5 and 7 and each may comprise a post 58 having a hole 59 in the center to receive 45 one of the pins of the plug to be hereinafter described.

The receptacle 17 also contains an automatic switch for disconnecting the power supply to the control box 13. To this end a metal plate 61 is 50 secured to the base 60 as by suitable screws 62 and is provided with a contact 63 which normally engages a second contact 64 mounted on a plate 65 secured to the base 60 by means of a suitable screw 66. Normally the contact 25 of the main 55 control box 13 would be connected to the power side of the circuit by means of the wire 67 but in the present instance this wire is extended to pass through the conduit 18 and is connected to the switch plate 61. A wire 68 is connected between 60 the plate 65 and the contact 25 in the control box 13. When the two contacts 63 and 64 are touching each other, as they normally are, the contact 25 in the main control box 13 will be connected to power by means of the wire 68, but when these 65 contacts are separated the power supply to the contact 25 is cut off.

The auxiliary control box 19 comprises a casing in which is mounted an arm 69 similar to the arm in the main control box 13 so that it will rotate 70 through a limited distance about a pivot point 70. The arm 69 protrudes through a suitable slot 71 in the casing and is provided with a handle 72 for grasping it conveniently. The arm 69 carries an 75 arcuate contactor member 73 which is adapted to

make the necessary contacts when the arm is moved in either direction about the central position as shown in Fig. 2. An arcuate insulating block 74 is provided mounted directly beneath the contactor member 73 and a plurality of contacts 75, 76, and 77 are mounted on this block and extend outwardly into the path of the main contactor member 73. A central contact member 78 corresponds to the contact 25 in the main control box and preferably is provided with a centrally cut out portion 79 which provides a space between it and the contactor member 73 when the latter is in its central or neutral position. The ends of the contact member 78 are raised to the same level as the contacts 75, 76, and 77 and provide 10 a contact 80 adjacent the contact 75 which may be bridged by the contactor 73 when the arm is moved toward the left or in a counter-clockwise direction. The contacts 75, 76, and 77 are connected respectively by the wires 81, 82, 83, to the 15 split pin terminals 84, 85, and 86 in the plug 21. These wires are contained in the cable 20. The contacts 75, 76, and 77 in the auxiliary control box constitute the three lower "up" speeds and correspond to the contacts 36, 37, and 38 of the 20 main control box 13.

In like manner three "down" contacts 87, 88, and 89 are provided on the right hand side of the insulating block 74 of the auxiliary control box and are adapted to be contacted by the contactor 30 73 when it is moved toward the right, an additional contact 90 being provided at the right hand end of the contact 78 to connect the contactor 73 to the power supply. These three contacts 87, 88, and 89 are connected by means of wires 91, 92, 93 to the split pin terminals 94, 95, 96 in the terminal plug 21.

The contact 78 in the auxiliary box is connected by means of a wire 97 to a flat terminal pin 98 provided in the plug 21. This flat pin 98 is adapted to contact with two prongs 99 attached to the plate 61 in the receptacle 17 and to thereby connect the contact 78 with the power circuit. An insulating plug 100 having the same general shape as the pin 98 is also provided in the plug 21 and 45 is adapted to pass between the contacts 63 and 64 when the plug is inserted into the receptacle, thus 50 breaking the power connection to the contact 25 of the main receptacle.

If desired a weight 101 may be provided on the 55 lower end of the arm 69 of the auxiliary control for normally returning the control to its neutral central position by gravity, and a pin 102 may also be provided in the upper end of the arm 69 to engage a notch 103 in an arcuate plate 104 provided on the top of the box 19. The pin 102 may be urged outwardly by a spring 105 and may be connected to the handle 72 by a pin 106 so that the pin 102 may be moved to clear the notch 103 by pulling the handle 72. By this construction 60 the controlling arm may be automatically locked in neutral position so that the car cannot be started unless the operator pulls the handle 72 outwardly.

Also I prefer to mount the auxiliary control box 65 19 on a convenient part of the elevator roof where it may be easily reached from any position on the car. As shown, the box is mounted directly on one of the cables 12 by means of two clamping bars 107 which securely hold the cable between 70 them and the control box 19 when the wing nuts 108 are tight. Any other convenient method of 75 mounting the control box, however, may be utilized, such as a bracket especially made for that purpose and mounted on the top of the car, or if 78

desired the mechanic may carry the control box strapped to his own person.

When the mechanic is ready to inspect the cables of the elevator car or make any necessary repairs or adjustments from the roof thereof he will stop the car at a floor level, open the car door and the door of the shaft, and after inserting the plug 21 into the receptacle 17 he will step out of the car on to the floor. Standing on the floor he will then move the auxiliary control handle 72 toward the right as shown in Figs. 2 and 4 which will start the car downwardly. When the roof of the car comes level with the floor he will move the handle again to its neutral position and then step on to the roof of the car whereupon he will close the shaft door. He will then secure the control box to one of the cables as indicated in Fig. 1, and he may then make his necessary repairs, inspection, or adjustments controlling the movement and speed of the car by manipulating the control box himself. When he is through making the repairs, adjustments, or inspection he will move the car so that the roof thereof is even with one of the floors, open the shaft door, remove the control box from the cables, step out on to the floor, move the handle 72 of the control box toward the up position or toward the left whereupon the car will move upwardly, return the handle to its neutral position when the floor of the car reaches the floor level, step into the car, remove the plug 21, and the car will then be ready to operate in its normal manner.

Due to the fact that the main contact of the regular control box 13 is disconnected from its power supply by means of the plug 100 which separates the contact point 63 and 64 in the receptacle 17, no one can move the car from the main control box when the auxiliary control box is in neutral position and hence the mechanic on the roof is protected against accidental movement of the car. As the "up" and "down" contacts in the auxiliary control box are connected to the contacts in the regular control box the latter contacts become energized when the auxiliary control is being used. It is possible therefore by moving the regular control handle to increase the speed of the car in which ever direction it is moving under control of the auxiliary control box; but it is impossible to energize the "up" contacts, for instance, when the auxiliary control box is set for "down", or vice versa, and it is always possible to stop the car by throwing the auxiliary control handle to its neutral position regardless of the main control box as this removes the power from all of the contacts.

Also it will be noted that if the plug 21 is inadvertently pulled out of the receptacle 17 the car will immediately stop and the main control box will remain in its neutral position and will then be connected.

While any number of speeds may be provided in the auxiliary control I preferably limit the speeds to the slower ones or those which are absolutely essential for making necessary tests on the car which I believe is an added safety precaution for the mechanic using the device.

While one type of elevator controlling mechanism has been illustrated it is evident that the invention is adaptable to any type of electrical elevator control and may be used on other systems, the essential features being a control box similar to the control box in the car, means to connect the two together, and means to disconnect the power from the main box when the auxiliary control is connected. This latter

means may, of course, be dispensed with but is an added feature of safety.

Many other modifications of the invention may be resorted to without departing from the spirit thereof, and I do not therefore desire to limit myself to what has been shown and described except as such limitations occur in the appended claims.

What I desire to secure and claim by Letters Patent is:

1. In elevator controlling apparatus a regular control box for the elevator, a remote control box for the elevator, releasable means for connecting said auxiliary control box to said regular control box, and automatic means for disconnecting the power supply of the regular control box when the auxiliary control box is connected.

2. In elevator control apparatus a portable control box, an extensible cable connected to said control box, releasable means to connect said cable to the regular controlling apparatus of an elevator, and automatic means to disconnect the power supply of said regular controlling apparatus when said auxiliary control box is connected.

3. A controlling attachment for elevators comprising an auxiliary control box provided with power and control contacts, a flexible cable connected to said control box a controller attached thereto, a plug on the end of said flexible cable, a main control box provided with power and control contacts, means to electrically connect the control contacts only of said main and auxiliary control box when said plug is inserted in said receptacle, and a second controller attached to the main control box.

4. In an elevator control system a receptacle permanently positioned in each elevator car, a plurality of contacts in said receptacle, means to connect said contacts with the contacts of the regular control apparatus, an auxiliary control box, a plurality of contacts in said auxiliary control box, a plug, a plurality of contact pins on said plug, means to connect said pins to the contacts in said auxiliary control box, and means to selectively connect the contacts in said auxiliary control box to the contacts in the regular elevator control apparatus when said plug is inserted in said receptacle and to disable the regular control.

5. In a system for elevator control a regular control box for an elevator car, a receptacle permanently mounted in the car, a plurality of contacts in said receptacle, means to connect said contacts to the "up" and "down" contacts in the control box, an auxiliary control box, a plurality of contacts in said auxiliary control box corresponding to the contacts in said regular control box but being less in number, a plug, contact pins on said plug adapted to fit into the contacts of said receptacle, a flexible cable connecting said plug with said auxiliary control box whereby said pins are selectively connected to the contacts in said box, a bridging contactor in said regular control box, a bridging contactor in said auxiliary control box and means to disconnect the power side of the circuit from said bridging contactor in said regular control box and connect the power side of the circuit to the bridging contactor in said auxiliary control box when said plug is inserted in said receptacle.

6. In an elevator having a control box with a plurality of speeds up and a plurality of speeds down, an auxiliary control box, an "up" contact in said box, a "down" contact in said box, a third contact in said box adapted to connect alter-

- natively with said "up" contact or "down" contact, flexible means to releasably connect said contacts with one of the "up" contacts and one of the "down" contacts in said regular control box and to connect said third contact to the power side of the circuit, and automatic means for disengaging the regular control box when connection has been established between the regular and auxiliary control boxes.
10. 7. In an elevator controlling apparatus a main control box for the elevator, an auxiliary control box for the elevator, control contacts in said boxes, disconnectable electrical circuit connections between the two sets of control contacts only, means in said auxiliary control box for establishing a closed circuit through the circuit connection, and means in said main control box for varying only the current flow through said circuit connection.
15. 8. In an elevator control apparatus a power circuit for the elevator, control circuits for the elevator, means for controlling direction and amount of current flow through said control circuits, and additional means operative only when said first means is operative for varying only the amount of current flow in the control circuit.
20. 9. The combination with an electric elevator of a main control box, an auxiliary control box, control contacts in said boxes, connections between the sets of contacts in the two boxes, man-

ual control means at the auxiliary box to establish a circuit through said connection, means at the main control box for varying only the amount of current in said connection, and means for automatically breaking the circuit flow through said connection when the manual auxiliary control means is released.

10. 10. In an electrical controlling apparatus a main control box for the elevator, an auxiliary control box for the elevator, control contacts in said boxes, the number of contacts in the main control box exceeding that in the auxiliary control box, disconnectable electrical circuit connections between all of the control contacts of the auxiliary box and a corresponding number of contacts in the main box, a contactor brush in said auxiliary control box for establishing a closed circuit through the circuit connection and a contactor brush in said main control box for connecting the unconnected contacts to the circuit connection.

15. 11. In an elevator control apparatus a power circuit for the elevator, control circuits for the elevator, a first controller for starting, stopping, reversing, and accelerating the movement of the elevator, and a second controller electrically connected to said first controller for accelerating only the movement of the elevator.

FREDERICK A. PAVONE. 30
